UNITED STATES PATENT OFFICE.

THOMAS GREEN, OF SIOUX CITY, IOWA.

BRICK-KILN.

SPECIFICATION forming part of Letters Patent No. 514,709, dated February 13, 1894.

Application filed June 26, 1893. Serial No. 478,853. (No model.)

To all whom it may concern:

Be it known that I, THOMAS GREEN, a citizen of the United States, residing at Sioux City, in the county of Woodbury and State of

5 Iowa, have invented certain new and useful Improvements in Brick-Kilns; and I do declare the following to be a full, clear, and exact description of the invention, such as will enable others skilled in the art to which it 10 appertains to make and use the same, reference being had to the accompanying drawings, and to the letters of reference marked thereon, which form a part of this specification.

15 My invention relates to continuous brick kilns, and the object is to provide flues to regulate the draft and progress of the fires and to utilize the surplus heat of the burning chambers.

20 My invention is a modification of my continuous brick kiln, for which application, Serial No. 389,718, was filed on the 20th day of April, 1891, and to which reference is respectfully made.

25 The invention consists, therefore, in novelty of construction, the arrangement of parts and the combinations thereof, as will be hereinafter more fully pointed out.

I have fully illustrated my invention in the 30 accompanying drawings, wherein—

Figure 1 is a view of kiln in side elevation. Fig. 2 is an enlarged detail plan view, partly in section, of portion of kiln taken in line 7—7, Fig. 3. Fig. 3 is a detail cross-sectional view of Fig. 2. Fig. 4 is an enlarged detail view of damper, used in short flues, as shown in Fig. 3. Fig. 5 is an enlarged detail view of damper, or check draft, used in the overhead flue, as shown in Fig. 3.

40 Referring now to these illustrations, wherein like parts are designated by similar letters of reference, *a a* represents the outer walls of the kiln, *b b*, the wall portion of the kiln between the main chambers and the smoke chamber.

45 *i i⁴* are dampers, one being located at the inner end of the flue *C*, Fig. 3, and consists of a cap, which may be drawn up to open, or let down to close the draft. *j j²* is another kind

50 of damper used in the short flues *F*.

k k are fire holes located in the top of the

kiln, adapted to be fed and regulated from above, each being provided with a removable cap.

L is the smoke-stack located in the center 55 of the kiln.

m m is the frame roof of the kiln.

A, A², &c., are the continuous chambers extending around the outside of the kiln, and capable of being entered through the openings *X X*, as shown in Fig. 1.

c c, Fig. 2, are partitions separating the chambers *A, A², &c.*

B is the smoke chamber located longitudinally between the chambers in the center of 65 the kiln, and communicating directly with the smoke-stack *L*.

C is a flue leading directly from each chamber of the kiln over the top of the chamber into the smoke chamber. The dampers *i i⁴* controlling this flue, are so located that they may be easily reached and repaired when out of order.

G is a continuous flue passing around the center of this kiln between the chambers *A 75 A², &c.*, and above the smoke chamber.

F F are short flues leading directly from every chamber *A A², &c.*, into the continuous central flue *G*. They are regulated by the dampers *j j², &c.*, which are located in the 80 flues *F*, near the flue *G*. By closing the damper in the flue *C*, thus shutting off communication with chambers ahead, the surplus heat is drawn from any chamber through the flue *F* into the continuous flue *G*; thence, 85 by regulating the damper in the short flues, it may be conducted into any desired chamber, and there mingle with the heat in the burning chamber. Thus, as shown in Fig. 3, damper *i* is closed, shutting off communication between chamber *A* and the smoke chamber. The brick in *A* is burned and in *A²* is burning, while in *A³* and *A⁴* the green brick is just set and ready to be fired. It is desired to conduct the heat from *A* past *A²* into 95 *A³* and *A⁴*. Dampers *j, j³* and *j⁴* are opened and *j²*, and the heat is drawn from *A* past *A²* and into *A³* and *A⁴*, as shown by the direction of the arrows.

Having described my invention, what I 100 claim as new, and desire to secure by Letters Patent, is—

The combination in a continuous brick kiln, of a series of drying chambers, a smoke chamber located between said drying chambers, and draft flues leading from the outer walls of the drying chambers over said chambers and into the smoke chamber, substantially as described.

In testimony whereof I affix my signature in presence of two witnesses.

THOMAS GREEN.
